UNITED STATES PATENT OFFICE.

WILLIAM W. MITCHELL, OF NEW HAVEN, CONNECTICUT.

LUBRICATOR.

SPECIFICATION forming part of Letters Patent No. 250,944, dated December 13, 1881.

Application filed May 12, 1881. (No model.)

To all whom it may concern:

Be it known that I, WILLIAM W. MITCHELL, a citizen of the United States, resident of New Haven, in the county of New Haven and State 5 of Connecticut, have invented a new and valuable Improvement in Lubricators; and I do hereby declare that the following is a full, clear, and exact description of the construction and operation of the same, reference being had to 10 the annexed drawings, making a part of this specification, and to the letters and figures of reference marked thereon.

Figure 1 of the drawings is a representation of a vertical section of my invention. Fig. 2 is a 15 detail view; and Figs. 3, 4, 5, and 6 are modifications.

This invention has relation to lubricators for locomotives and other steam-engines; and it consists in the combination, with the water 20 or condensing chamber and the oil-chamber, of a steam-chamber, and within the same a vapor-conductor.

It also consists in the construction and novel arrangement of the feed-passage for the oil, 25 the partition above the glass tube, and the passages or tubes connecting therewith, of the grooved feeding-plug and the bearings for the glass tube, and of other devices in connection with the steam-chamber, the condensing-chamber, and the oil-cup, as hereinafter 30 shown and described.

In the accompanying drawings, the letter A designates the boiler, to which the lubricator is attached; and B represents the steam-chamber 35 of the lubricator, into which steam is admitted from the boiler through a passage, a, which is provided with a valve, b, to cut off communication with the boiler. The steam-chamber is provided with a conductor or passage, c, connecting with the pipe d, which leads to the cylinder or valve-chest of the engine.

C represents the condensing or water chamber, which is provided with an interior upright tube, e, extending from the passage g, communicating with the steam-chamber nearly to the top of the water-chamber, as shown in the drawings. Through the passage g and the tube e steam passes into the chamber C, and, becoming condensed, descends in the form of 45 water through the passage h and tube k to the lower portion of the oil cup or reservoir D. The passage h is provided with a valve, b',

whereby the downward flow of the water is regulated or arrested altogether, according to requirement. Through the arm E, in which 55 the steam-passage g is arranged, an oil-passage, l, also extends, being provided with a regulating or cut-off valve, b'', and with a spout or discharge, m, within the steam-chamber. 60

F indicates a glass tube or water-sight, arranged in oil-tight bearings n, into which it is passed through an opening, p, which is afterward closed by means of the screw-plug G, having a circumferential groove, r, and passages s, through which oil is fed to the water-glass F. The circumferential groove r permits a constant flow of oil, whereas if no groove were employed and the plug screwed either too little or too far, the passages would 65 not align, and a meager flow of oil would result. Into the upper end of said water glass or tube F extends one end of a tube, l', passing through a wall or bearing, t, above said glass F, and separating the latter from the 70 oil-filling passage H. The other end of the tube l' connects with the oil-passage l in the arm E. The passage H, leading to the oil cup or reservoir D, is closed at the outer end by means of the screw-plug K, which engages 75 with the threaded opening u. From the lower end of the oil-cup extends upward nearly to the upper end of the same a tube, v, which connects at its lower end with an oil-passage, w, which extends to the feed-plug G at the 80 lower end of the glass tube F.

L indicates the water-discharge, having the valve b''.

The operation of the lubricator is as follows: Steam is admitted to the steam-chamber B 85 from the boiler, and passing thence into the chamber C is condensed and carried downward through the passage h and tube k into the oil-chamber D, raising the oil therein, which flows down the tube v and through the passage 90 w and plug G into the glass tube F. This tube is designed to have been previously filled with the water of condensation, and the oil passes upward through the water in the form of visible drops, indicating the rapidity of feed. The 95 oil passes from the glass tube, through the tube l' and passage l and spout or tube m, out into the steam-chamber at or near the mouth or wall of a conducting-passage, c, where it is 100

vaporized and commingled with the particles of watery vapor, and passes through the conductor or passage *c* in the form of greasy steam to the pipe leading to the cylinder, valve-chest, 5 or steam-pipe of a locomotive or steam-engine.

It is evident that many slight alterations in the construction of a steam-chamber can be made for accomplishing the same result; and I do not, therefore, limit myself to the exact 10 construction herein shown and described.

Having described this invention, what I claim, and desire to secure by Letters Patent, is—

1. In a lubricator, the combination, with a 15 condenser, *C*, and an oil-chamber, *D*, of a steam-chamber, *B*, and within the same a vapor conductor or passage, *c*, substantially as specified.

2. In a lubricator having a glass sight-tube, 20 an oil-passage, *l*, a tube, *l'*, an oil-reservoir, and the bearing *t* at the top of the glass tube forming the wall of the oil-filling passage, substantially as specified.

3. In a lubricator, the open lower bearing 25 for the lower end of the glass tube and the grooved feed-plug *G*, having the passages *s*,

in combination with the oil-passage *w*, substantially as specified.

4. In a lubricator, the combination, with the glass tube *F*, the steam-chamber *B*, the oil-chamber *D*, and the condenser *C*, of the steam-passage *g* and tube *e*, the water-passage *h* and tube *k*, and the oil-passages *l w* and tubes *m l' v*, in connection with the valves *b' b''*, substantially as specified. 35

5. A steam-reservoir for lubricators having an oil-discharge, *m*, and a vapor conductor or passage, *c*, substantially as specified.

6. In a lubricator, the combination, with the oil-reservoir, of the wall or partition over the 40 glass tube forming the oil-filling passage *H*, and the feeding-tube *l'*, extending through said filling-passage to the oil-discharging passages *l* and *m*, substantially as specified.

In testimony that I claim the above I have +5 hereunto subscribed my name in the presence of two witnesses.

WM. W. MITCHELL.
